UNITED STATES PATENT OFFICE.

JOHN H. SHEPHERD, OF ELYRIA, OHIO.

METAL-WORKING MACHINE.

1,366,425.

Specification of Letters Patent. Patented Jan. 25, 1921.

Application filed July 10, 1918. Serial No. 244,292.

To all whom it may concern:

Be it known that I, JOHN H. SHEPHERD, a citizen of the United States, residing at Elyria, in the county of Lorain and State of Ohio, have invented certain new and useful Improvements in Metal-Working Machines; and I do hereby declare the following to be a full, clear, and exact description of the invention, such as will enable others skilled 10 in the art to which it appertains to make and use the same.

My invention relates to metal working machines, employed, for example, in the manufacture of such devices as the float illustrated and described in United States Letters Patent No. 1,230,335, June 19, 1917. It is very important that such structures should possess great rigidity and strength, in order to resist blows and strains delivered to them, and should, at the same time, be light and buoyant. When made of sheet metal it is, therefore, important that such strength and rigidity shall be realized by the structure of the device and the manner 25 in which it is constructed.

I have mentioned this particular structure for the purpose of describing my invention. It will, of course, be apparent that my invention may be employed in the making 30 of any similar structure where such functions as I have named are important.

I aim to produce a machine which will so operate upon the metal as to produce a structure realizing the advantages I have named, 35 and which is of especial advantage in making the devices illustrated in my said former patent.

I also aim to produce a machine which will quickly, cheaply and conveniently perform such functions.

Other objects of my invention and the invention itself will be better understood from a description of an embodiment of the invention.

45 Figure 1 is a top plan view of an embodiment of my invention.

Fig. 2 is a side elevation showing a partially made float in position.

Fig. 3 is a sectional view along the line 50 3-3 in Fig. 1.

Fig. 4 is a sectional view along the line 4-4 of Fig. 1.

Fig. 5 is an end elevation looking in the direction of the arrow 5 in Fig. 1.

Referring now to the drawing and to the 55 embodiment of the invention shown therein, at 6 is shown the base of the machine, which is here illustrated as made of a casting provided with a longitudinal opening 7. The base is a hollow rectangular member provided with ears 8 through which it may be attached to any supporting means. At 9 and 10 are shown the tool members. As here illustrated, these members are shaped like a hollow cone. While the exterior may 60 be of any suitable shape, it is important that the interior or cavity shall be cone, or approximately cone, shaped. In the embodiment here shown the walls of these cavities, here called the faces of the tool members, 65 are indicated at 11, and are cone-shaped, since it is here desired to produce floats with cone-shaped ends. These faces 11 are provided with a plurality of ribs 12, which extend in a direction parallel to the elements 70 of the surface of the cones. In the embodiment shown, the ribs begin at the base of the cone and extend part way to the apex near which they terminate, as indicated at 75 13, at points equidistant from the apex of 80 the cones. The ribs should be equally spaced apart, and should extend all around the interior of the tool member.

The tool at 9 is preferably formed of two parts, a part 14 consisting of a hollow frusto- 85 conical member carrying the ribs 12 and having its edge beveled off, as illustrated at 15 in Figs. 1 and 2. The other part 16 contains a recess 17, which is substantially conical in shape, and whose base is the same 90 area as the opening 141 in the top of the recess in the part 14. The member 16 also contains a cylindrical bore 18, through which the tool member 9 is connected to a movable shaft 22 by any suitable means, 95 such as a set-screw 20 and a slot 21.

In the embodiment shown, the shaft 22 is provided with an annular slot 21, and the set screw 20 passing through a bore 200 in the shank 142 of the part 16 has its end 201 100 situated in said slot. The set screw is adapted to be driven against and grip said shaft to "set" the tool member in position in said shaft.

The parts 14 and 16 are fastened together 105 in any suitable manner, such as by screws 23. The part 10 is composed of the part 14', which may be similar to the part 14 of

the tool member 9. The second part 16' of the tool member 10 is formed with a conical recess 17' whose base is the same area as the area of the opening in the top of the recess 5 in the part 14'. The part 16' is provided with a cylindrical shaft 25, which is mounted in a cylindrical bore 26 in a supporting member 27. The member 16' is movable longitudinally in the bore 26. Means are 10 provided for moving this member longitudinally, here consisting of a shaft 30 provided with a spiral thread 31, which operates in a bore 32 in the member 27. A pair of lugs 33 are formed in the walls of the bore 32, 15 performing the function of the female threads.

The shaft 30 is rotated through an arm 35, and the member 17' thereby driven longitudinally, for a purpose to be described.

20 The frame member 27 is mounted on the base and is adjustable therein in a well known manner, as illustrated in Figs. 1 and 2. The member 27 is provided with flanges 271 and 272, which fit over the top of the 25 flanges 60 and 61 on the base 6. The member 27 is also provided with a flange 273 adjustably mounted on the bottom of the member 27 to grip the bottom of the flanges 61 and 62. It will thus be seen that the member 30 27 may be moved to a desired position on the base and there fastened. Means are provided for bracing this member and the apparatus carried thereby in the frame, here shown as a rack 40 and a catch 41. The rack 35 40 is pivoted at 42 to the member 27, so that the rack teeth 400 engage the catch 41. The rear end 43 of the rack may be lifted when the position of the member is to be changed. It will be seen that these means enable me to 40 quickly change the position of the member 27 and always to brace the same.

The tool 9 and the shaft 22 are mounted in a second frame member 50, which is here shown as provided with two uprights 51 and 45 52, each of which is provided with an opening 54 through which the shaft 22 extends and through which it is movable longitudinally. Means are provided for moving this shaft longitudinally, here consisting of a 50 lever 60 pivoted at 61 to the member 50 and connected through links 62 with a lug 63 secured in turn to the shaft 22 by some such means as a set-screw 64. I prefer to make the member 50 adjustable on the base, for 55 example, in the same manner as the member 27.

Means are provided for retaining the mechanism in the position to which it has been moved when the lever 60 has been moved 60 to its farthest right-hand position (referring to Figs. 1 and 2) and in which the float is caught between 9 and 10, while the operation caused by movement of 35 is being effected. In the embodiment shown I have provided 65 for this purpose a device 113 pivoted at 114

to the block 63 and which may slide along the top of 50 and when 60 has reached its farthest right-hand position, drops down behind 50, so that the end of 113 will engage the side of 50 and lock 60 in such position. By 70 lifting 113 so as to clear the side of 50, lever 60 is released and can be thrown back.

The operation of the embodiment of my invention illustrated and described is as follows: The device to be operated on is 75 shown at A and is constructed by cutting a piece of sheet metal to the desired size, forming the same with the corrugations B and with the creases C. As will be seen, the corrugations are in the central part of the device and are perpendicular to the creases C at the ends of the device. The sheet metal thus creased and corrugated is formed into a cylinder, as illustrated in the drawing, the seam along the edge being closed in any suitable manner.

The device thus formed is placed in the machine with the ribs 12 in the grooves D in the device, as illustrated in Fig. 2. The lever 60 is then moved in the direction of the arrow X, moving the tool member 9 toward the tool member 10, the ribs all the while running along the grooves D. In the embodiment shown, the ribs following the direction of the conical cavity, gradually and 90 with pressure uniformly exerted about the periphery of the end of the cylinder, draw the ends of the cylinder together, forming conical parts at the ends. The height of the corrugations of these conical parts is increased as the ends are approached, thus 95 making the floats especially strong at the ends. The conical parts are corrugated and thus strengthened to resist any blows delivered to them. This operation progresses 100 gradually as the tool members are brought together.

Toward the end of this operation, the ends of the devices A are rammed down into the conical recesses 17 and 17'. It will be 110 seen, however, that owing to the fact that the ribs do not extend to the apex of the cone, the ends of the conical sections of the device will pass into the unribbed portions of the conical recesses shown at 17 and 17', 115 thereby preventing the jamming of the metal in the machine.

When the ends of the corrugations so pass the ends of the ribs, the grooves D will be 120 substantially the width of the ribs themselves. If the ribs were continued further, the machine would jam.

When the lever 60 has been moved as far in the direction of the arrow X as possible, the arm 35 is thrown over, moving the member 16' longitudinally, and still further drawing down the end of the device A, which is in the tool 10. When this operation has been completed, the device A is removed and 125 reversed and the other end thereof still fur- 130

ther drawn down by the use of the device 17'. The member 16', when operated as described, serves to draw the ends of the devices A still further together, reducing the 5 width of the grooves D to a minimum at the ends of the parts C, and increasing the strength of these parts. The openings in the ends are thereby closed, or reduced to a minimum, so that they can readily and easily 10 be closed in some such manner as described in my former patent.

Of course, the operations are effected in much less time than is consumed in describing them. The machine is simple, and its 15 operation can be effected by one unskilled.

While I have shown this particular embodiment of my invention and the details thereof, it will be apparent to those skilled in the art that numerous and extensive 20 departures may be made therefrom without departing from the spirit of the invention.

I claim:

1. In a sheet metal working machine, the combination of a pair of tool members, each 25 provided with a cone-shaped cavity, longitudinal ribs mounted in said cavities and equally spaced apart therein, said ribs extending clear around the faces of the cavities and beginning adjacent the edges of the 30 mouths of the cavities and extending part way only to the apices thereof, means to mount said tool members with the cavities facing each other, means to move one of said tool members toward the other, a movable 35 device mounted in the apex of one of said cavities, and having a conical recess therein whose base is coincident with the top of one of said cavities and mechanism to move said device toward said cavity.

40 2. In a machine of the class described, the combination of a pair of tool members, each provided with a cavity therein, means to mount said tool members with the cavities facing each other and means to move one 45 of said tool members toward the other, a device movably mounted at the bottom of one of said cavities and adapted to be moved in the direction of the other tool member, and mechanism to move said device in the 50 direction of the other tool member.

3. In a machine of the class described, the combination of means to engage the bottom of corrugations formed in the end of a cylindrical sheet metal device and to draw said 55 ends together, thereby increasing the depth of the corrugations so that the depth is greatest at the ends thereof, and mechanism to engage the ends of the corrugations thus formed to still further close the end of 60 the cylinder, thus forming rigid cone-shaped ends to the cylindrical device.

4. In a sheet metal working machine, the combination of a pair of members each provided with a cone-shaped cavity, a plurality 65 of ribs on the face of each of said cavities

extending parallel to elements of the surfaces of the cavities, means to mount said members with the cone faces of the cavities facing each other, means to move one of said members toward the other and a device to 70 lock said means in position when so moved.

5. In a machine of the class described, the combination of a pair of members provided with cone-shaped faces oppositely mounted, a plurality of ribs in each face extending 75 along the cone-shaped face thereof and parallel to the elements of the surface thereof, means to move one of said members toward the other and a device to lock said means in position when so moved.

6. A tool member for compressing the ends of tubular devices, consisting of a die having a conical recess, a supporting member secured to said die having a recess communicating with the end of said conical 85 recess, a second die having a conical recess and slidably positioned in the recess in said supporting member, and means for moving said last mentioned die.

7. A tool member having a die with a 90 conical recess, said die having a plurality of grooves arranged in the surface of said recess, ribbed members in said grooves, a supporting member secured to said die and having a recess communicating with the 95 first-mentioned recess, a second die having a conical recess and adapted to slide in the recess in said supporting member, a screw threaded in said supporting member and bearing against said last mentioned die 100 whereby the second mentioned die is moved by rotating the screw.

8. In machines for closing the ends of tubular devices, tool members having cone-shaped cavities, a supporting bed, means 105 for mounting the members on said bed with the base of the cone-shaped cavities toward each other, means for moving one member to compress the ends of a tubular device in said cavities, whereby the said ends are 110 drawn into conical shape, and a die having a conical recess and adapted to slide in one of said members to further compress the end of said device.

9. In machines for closing the ends of 115 tubular devices, a tool member having cone-shaped cavities, a supporting bed, means for mounting the members on said bed with the base of the cone-shaped cavities toward each other, ribbed members arranged in said 120 conical cavities, means for moving one member to compress the ends of a tubular device in said cavities, whereby the said ends are drawn into conical shape, and a die having a recess and adapted to slide in one of said 125 members to further compress the end of said device.

10. In a machine for closing the ends of 130 tubular devices, tool members having cone-shaped cavities, a supporting bed, means for

mounting the members on said bed with the base of the cone-shaped cavities toward each other, means for moving one member to compress the ends of a tubular device in said cavities, means for locking said last mentioned member after being moved by said means, a die positioned in the other of said

members, and means for moving said die in said member to further compress the end of said device.

10

In witness whereof I hereunto sign my name this 3rd day of July, 1918.

JOHN H. SHEPHERD.
